UNITED STATES PATENT OFFICE.

FRANCIS FEENEY, OF MANCHESTER, ENGLAND.

RE-TURNING MACHINE FOR MANUFACTURING SHOES.

SPECIFICATION forming part of Letters Patent No. 771,975, dated October 11, 1904.

Application filed December 30, 1903. Serial No. 187,242. (No model.)

To all whom it may concern:

Be it known that I, FRANCIS FEENEY, a British subject, and a resident of Manchester, in the county of Lancaster, England, have invented 5 certain new and useful Improvements in Re-Turning Machines for Manufacturing Shoes, of which the following is a specification.

In the manufacture of shoes and slippers the uppers are sewed or stitched to soles 10 while inside out, and it is necessary then to turn both the heels and the fore parts over to bring the right side outermost. This when done by hand, as is usually the case, is a very troublesome and tiresome task entailing considerable labor and time. This invention is 15 designed to provide apparatus by the assistance of which the operation can be performed very quickly and with ease and but little exertion on the part of the operative.

It consists, essentially, in apparatus 20 constructed with a long pointed or narrow beak of a shape to fit into the fore part or toe of a slipper, the lower part of which is pivoted to open to grip the heel and facing the beak a tubular or other bracket to support a movable toe-shaped half last or block between it and the end of the beak.

The invention will be fully described with 25 reference to the accompanying drawings.

Figure 1 is a side elevation of the apparatus, showing parts in position for turning the 30 heels of shoes and slippers; Fig. 2, a side elevation showing parts in position for turning over the fore parts of shoes and slippers; Fig. 3, a plan, partly in section, of Fig. 1; Fig. 4, a plan of Fig. 2.

The apparatus is constructed with a long beak-shaped stand or bracket A, placed at some distance from the base B upon a curved 40 upright or support C. The beak-shaped stand A is made in two jaws a a', pivoted together, so as to open and close. The lower jaw a' is movable and is of bell-crank or other similar form, with a member a'', by which it 45 is operated to clamp it upon anything placed between the jaws. The two jaws a a' are forced together by a toggle-lever D, operated by a rod E, connected with a treadle or other lever. One end of the toggle-lever D is pivoted to the bell-crank member a'' of the mov-

able jaw a', and the other end is pivoted to a collar d, carried on a screw F, passed into the upright C, by which the movement of the toggle can be adjusted to apply more or less pressure to the jaws. The lower jaw a' is 55 preferably made to project somewhat beyond the upper one to form a rest for the toe of the shoe or slipper when turning over the fore part.

In front of the beak-shaped stand A is 60 placed a bracket K, pivoted on the top of a pillar L, capable of swinging from a horizontal to an inclined position (see Fig. 1) and drawn back by a spring M. The bracket K is tubular, preferably, with a spring k in the 65 interior to receive the end of a rod n, attached to a half last or block N, which fits into the fore part of the shoe or slipper.

For turning the fore part of slippers only the beak A may be made without the lower or 70 opening part, with a projection to support the toe of the last N.

In operation to turn the heel of the shoe or slipper the back of the heel is firmly gripped in the beak with the toe of the shoe hanging 75 down. The toe is raised by the operative over or around the point of the beak, thus turning the right side of the heel outermost. The fore part of the slipper is then fitted onto the half-last N and is supported on the rod 80 n in the bracket K with the toe of the slipper resting on the projecting tongue or under part of the beak. When in this position, the shoe is gripped by the operative and pulled forward off the last over the beak, turning it 85 right side out.

What I claim as my invention, and desire to protect by Letters Patent, is—

1. An appliance for turning the heels and fore parts of shoes and slippers, comprising 90 in its construction a beak-shaped bracket A of a shape to fit into a slipper, with a fixed jaw and a clamping-jaw to grip the heel, a depending lever to operate the clamping-jaw, and an adjustable toggle-lever connected to 95 the lever by which the jaw is opened and closed, substantially as described.

2. In appliances for turning the heels and fore part of turn-over shoes and slippers, the 100 combination with a beak-shaped bracket con-

structed with two jaws over which the shoe is turned, the lower jaw projecting beyond the upper one to form a rest for the last, a pivoted bracket K placed in front of the said 5 beak-shaped bracket and a half-last supported thereon, the toe of which rests upon the projecting end of the lower jaw, substantially as described.

In witness whereof I have hereunto signed my name in the presence of two subscribing witnesses.

FRANCIS FEENEY.
